UNITED STATES PATENT OFFICE.

JOSEPH T. PAQUIN, OF CLAREMONT, NEW HAMPSHIRE.

FIRE-ESCAPE.

1,243,339.

Specification of Letters Patent.

Patented Oct. 16, 1917.

Application filed March 23, 1916. Serial No. 86,191.

To all whom it may concern:

Be it known that I, JOSEPH T. PAQUIN, a citizen of the United States, residing at Claremont, in the county of Sullivan and 5 State of New Hampshire, have invented certain new and useful Improvements in Fire-Escapes of which the following is a specification.

My invention relates to a fire escape, and 10 one object resides in providing fluid means for controlling the rate of descent and ascent of a cage for carrying persons.

Another object resides in providing means for starting and stopping the cage at the will 15 of those within the same.

A further object consists in providing means which, when the cage is vacated, will return the same to its highest position for use again.

20 With the above and other objects in view, I will now proceed to describe the specific embodiment of my invention as illustrated in the accompanying drawings forming a part of this specification, and in which:

25 Fig. 1 is a side elevation of a fire escape constructed according to my invention applied to a building, but with the cage in section.

Fig. 2 is a detail view of the fluid controlled mechanism for regulating the rate of descent and ascent of the cage, and showing the fluid cylinders in section.

30 Fig. 3 is a detail view of the means for starting and stopping the cage from within 35 the same.

Fig. 4 is an elevation of the ratchet mechanism employed in connection with the fluid-controlled mechanism, and

Fig. 5 is a central sectional view through 40 one of the fluid cylinders.

The invention, as shown in the drawings, is applied to the side wall A of a building and consists of brackets 1 extending outwardly from said side wall at right angles 45 and bolted thereto by means of the bolts 2. These brackets support two upright track members 3 having the flanges 4. At the top the said track members 3 are connected by a horizontal tie bar 5 which is bolted to 50 brackets 6. One of the track members 3 carries, at the top, uprights 7 in which is journaled a shaft 8 carrying the centrally located grooved pulley 9, and also carrying at one end a fixed crank disk 10 and at the other 55 end a loose crank disk 11. The crank disks 10 and 11 carry crank pins 12 and 13, re-

spectively, which are connected by means of the connecting rods 14 and 15 to piston rods 16 and 17 of pistons 18 and 19, respectively. The said pistons 18 and 19 work in cylinders 60 20 and 21 which are closed at both ends and the top and bottom of each cylinder is connected by passages 22 in which are located shut off valves 23 and flow regulating valves 24. Thus it will be seen that as the pistons 65 18 and 19 reciprocate in said cylinders 20 and 21, respectively, the fluid within is merely pumped from one end of the cylinder to the other or from in front of the piston to behind the same and vice versa. The fluid 70 employed is a liquid such as water or oil and therefore the speed of reciprocation of the pistons may be regulated by restricting the flow through the passages 22, and this may be done by regulating the valves 24. 75 Also, should it be desired to entirely prevent reciprocation of the pistons the valves 23 may be closed.

The crank disk 11, as before stated, is loosely mounted on the shaft 8. However, 80 the shaft 8 has fixed thereto, adjacent the crank disk 11, a ratchet wheel 25 which is engaged by the pawl 26 carried by the crank disk 11 and held in engagement by the spring 27. Thus when the shaft 8 rotates in 85 one direction the pistons 18 and 19 will both come into play, whereas, when the shaft 8 rotates in the other direction, only the piston 18 will come into play by reason of the ratchet mechanism employed in connection 90 with the crank disk 11. Upon the cross member 5 are mounted two upright supports 28 and 29, the former of which is located immediately adjacent an opening 30 in the cross member 5. Both the upright supports 95 28 and 29 carry sheaves 31 and 32, respectively. A cable 33 of considerable length is passed over the grooved pulley 9 and underneath the sheave 32 and thence over the sheave 31 and down through the opening 30, 100 whence it connects with an eye-bolt 34 in the top of a passenger cage 35 which is provided with members 36 slidably engaging the flanges 4 of the track members 3. The other end of the said cable 33 carries a weight 37 105 which slightly overbalances the weight of the empty passenger carrying cage 35, and thus the latter will always be maintained in its highest position. Adjacent the bottom of the track member 3 nearest which the 110 weight 37 is located, is provided an arm 38 which carries a pulley 39. A second pulley

40 is located opposite to this pulley 39, and a cable 41 is attached to the bottom of the passenger carrying cage 35 and runs over pulleys 40 and 39 and attaches the weight 5 37 thus by pulling on the cable 41 the cage may be brought down due to the fact that such pull will overcome the overbalancing effect of the weight 37.

The passenger carrying cage 35 is provided with an inwardly opening door 42 located in the wall of the cage adjacent the wall A. Within the cage is located a hand-wheel 43 which is carried by a spindle 44 threaded through the side of the cage adjacent one of the track members 3 and is provided with a shoe 45 for engagement with the flange 4 of said track member. Therefore by turning up the hand-wheel 43 so as to engage the shoe 45 with the flange 4 the passenger carrying cage 35 may be brought to a stop or reduced in speed. Also this arrangement is used to hold the cage in its uppermost position until the same is loaded with passengers. The operation is as follows:

Normally the valves 23 are open and regulating valves 24 adjusted so as to give the proper ascent and descent speeds. The cage then, by reason of the overbalancing effect 30 of the weight 37 is maintained in an upward position as shown in Fig. 1, and is locked in such position by the shoe 45 engaging the flange 4. Suppose then, that passengers step into the cage 35, the overbalancing effect of the weight 37 would then be nullified by reason of the weight of the passengers in the cage. Thus as soon as the shoe 45 is released from engagement with the flange 4 the cage will begin to descend, 35 such descent being very gradual due to the fact that both pistons 18 and 19 are operating by reason of the rotation of the shaft 8. However, once the cage is down and the passengers step out, the cage will begin to 40 ascend again due to the weight 37 and such ascent will be controlled by the operation of the piston 18, the piston 19 being idle during the ascent of the cage.

It will be seen that, by training the cable 50 33 beneath the sheave 32, when the cage 35 begins to descend or ascend an upward thrust will be imparted to said sheave 32

which will, at all times, guide and maintain the cable 33 in engagement with the pulley 9 so that no slippage of the cable 33 over 55 said pulley can take place:

From the foregoing description, it will be evident that I have provided a simple fluid-controlled fire escape which carries a passenger carrying cage which may be started 60 or stopped at any point from within the cage, and the speed of ascent or descent of which is positively regulated so that the same cannot drop at too rapid a rate.

While I have herein described a specific 65 embodiment of the invention, it is to be understood, that in practice, various modifications and changes in the arrangement and construction of parts may be resorted to without departing in any way from the 70 spirit and scope of the invention as defined in the appended claims.

I claim:

1. In a fire escape, the combination with a movable cage, of a shaft, a pulley fixed to 75 said shaft, a cable passing over said pulley and supporting said cage, a disk fixed on said shaft, a disk loosely mounted on said shaft, a ratchet connection between said loose disk and said shaft whereby movement of said shaft in one direction will cause said loose disk to rotate, a cylinder for each disk, a piston in each cylinder, and a crank connecting the pistons with their respective disks, substantially as described. 85

2. In a fire escape, the combination with a movable cage, of a shaft, a bracket supporting said shaft above said cage, a pulley affixed to said shaft intermediate the ends of the latter, a disk fixed to said shaft at one 90 end thereof, a disk loosely mounted on the other end of said shaft, a cylinder beneath each disk, a piston in each cylinder, a crank connecting each disk with its respective piston, a ratchet connection between said loose 95 disk and said shaft, and a cable passing over said pulley and supporting said cage, substantially as described.

In testimony whereof I affix my signature in presence of two witnesses.

JOSEPH T. PAQUIN.
